ELECTRO-MAGNETIC TYPEWRITER

Abraham E. Auerbach, La Mesa, Calif., assignor to Leon Fine & Associates, Highland Park, Ill., a partnership

Application October 16, 1956, Serial No. 616,306

7 Claims. (Cl. 197—84)

This invention is concerned generally with a typewriter, and more particularly with proportional spacing for an electro-magnetic typewriter.

In accordance with standard practice, the same space is allotted on the typed page by most typewriters, irrespective of the inherent width of the letter or character. Thus, for example, the letter "i" is a very narrow letter, whereas the letter "m" is a relatively wide letter. Nevertheless, almost all typewriters allot the same space on the typed page to both letters. Attempts have been made heretofore to produce a typewriter having proportional spacing, i. e., a typewriter in which variable widths are allotted to letters in accordance with the width of the letters. For example, the letter "i" may be considered to be one unit wide, the letter "o" two units, the letter "w" three units, and "m" four units. Such spacing gives the illusion of printing, and a page typed on such a machine is better looking and more impressive than one typed on an ordinary typewriter. Unfortunately, however, prior typewriters embodying this feature have been inordinately expensive.

Accordingly, it is an object of this invention to provide proportional spacing in a typewriter at relatively low cost.

A further object of this invention is to provide proportional spacing in a particular type of typewriter, wherein rebuilding of the typewriter is unnecessary, only the addition of further parts being required.

More particularly, it is an object of this invention to provide an electro-magnetic typewriter with proportional spacing wherein a variable magnetic path is used in connection with the type actuating electro-magnet to control the distance of carriage movement.

Other objects and advantages of the present invention will be apparent from the following description when taken in connection with the accompanying drawings, wherein:

Fig. 1 is a fragmentary side view, partially in section, of a typewriter embodying the principles of this invention;

Fig. 2 is an enlarged fragment of Fig. 1;

Fig. 3 is a horizontal sectional view taken substantially along the lines 3—3 in Fig. 2;

Fig. 4 is a view similar to a part of Fig. 3 and taken along the line 4—4 in Fig. 2;

Fig. 5 is a view similar to a part of Fig. 3 and showing a modification;

Fig. 6 is an electrical wiring diagram forming a part of the typewriter; and

Fig. 7 is a vertical sectional view taken substantially along the line 7—7 in Fig. 2.

Referring now in greater particularity to the drawings, and first to Fig. 1, there will be seen the usual typewriter platen 30 having a sheet of paper 32 in typing position thereon. The typing ribbon 34 is in its accustomed position in front of the sheet of paper, and on the opposite side thereof relative to the platen 30. The ribbon may be held in any suitable or known manner,

2

and operated by known mechanisms. A series of type bars 36 (only one being shown) of more or less conventional construction is pivotally mounted at 38. Hereinafter, reference will be made to the single illustrative type bar and the accompanying parts. It will be understood that all parts are multiplied, where necessary, in accordance with the necessary number of type bars. More specifically, the type bar 36 has a type head or pallet 40 having a type face 42 thereon adapted to engage the ribbon 34 in order to form a typing impression on the paper 32. The type bar is provided with a slug 44 of magnetically susceptible material such as soft iron, and this slug is mounted shortly below the type head or pallet by any suitable means. Conveniently, the slug would be welded or soldered in place. A stop or rest 48 is provided for all of the type bars to hold them in idle position, such position being shown by the dot-dash lines of Fig. 1.

For each type bar 36 there is provided a key lever 50 pivoted at 52 and having an up-turned outer end carrying a key 54 of known construction. A stop or rest 56 is provided beneath the inner end of all of the key levers, and a spring 58 for each of the key levers is provided to hold the associated key lever against the stop. On the inner end of each lever there is provided a pivotally mounted dog or jack 60, pivoted at 62. This dog or jack is urged by a spring 64 toward a stop 66. When engaging this stop, the dog or jack bears upwardly beneath a shoulder 67 on the type bar.

Depression of a key 54 and accompanying pivotal movement of the corresponding key lever 50 will cause the associated type bar 36 to be moved upwardly from the dot-dash line position of Fig. 1, through the dashed-line position, and into the solid line position in contact with, or substantially in contact with the ribbon 34. As the type bar 36 approaches this limited position, the jack or dog 60 pivots against the force of the spring 64 and slides off of the shoulder 67 as is shown in full lines in Fig. 1, thus freeing the type bar for partial return, as to the position shown in dashed lines. However, the force with which the type bar is moved into proximity with the ribbon 34 is by design not sufficient to make a typing impression, and additional means are employed for this purpose as now will be described.

The foregoing is in accordance with my copending patent application for "typewriter," Serial Number 581,421, filed April 30, 1956, and further in accordance with that application, an electromagnet 68 is positioned below the platen 30. The electro-magnet is provided with a pole piece 70 projecting toward the type bars, and is positioned so that the magnetic slug 44 of any type bar will be aligned therewith. The electro-magnet additionally includes an energizing coil 74, as will be understood.

A non-magnetic switch actuator or push member 76 extends across the top of the electro-magnet 68, and is mounted in any convenient manner (not shown) for reciprocating movement, i. e., movement from right to left or vice versa in Fig. 1. The switch actuator or push member 76 is positioned for abutment by an abutment section 78 on the type bar 36, and shortly below the type face 42. The switch actuator or push member 76 conveniently is provided with an insulated tip 80, and switch contacts 84 carried by resilient arms 86 insulatedly mounted on a fixed support 82 are forced into engagement when the resilient strips 86 are deflected by engagement of the insulated tip 80 therewith.

The electrical circuit as shown in Fig. 6 includes a full wave bridge rectifier 88 connected to a flexible cord 90 having the usual plug (not shown) thereon for insertion in any convenient electrical outlet. The positive side of the rectifier is connected to a junction point 92, while the negative side is connected to a bus 94. The

bus 94 is connected to one end of the coil winding 74, and the other end of the coil winding is connected to the fixed contact 96 of a relay 98. The relay includes a coil 100 wound on a core 102, and an armature 104 attracted toward the core against the force of the spring 106 normally holding the contacts of the relay open. The armature is connected to a bus 108, and this bus is connected through a resistor 110 of high value to the junction point 92.

One end of the relay coil 100 is connected directly to the bus 94, while the other end is connected through a wire 112 to one of the contacts 84. The other of the contacts 84 is connected through a wire 114 to the junction point 92.

A capacitor 116 normally is charged from the rectifier 88 through the high resistance 110. When a key is depressed and the type bar 36 is thrown toward the full line position of Fig. 1, in the manner previously described, the switch contacts 84 are brought into engagement. This causes energization of the relay 98, the armature 104 thereby closing against the fixed contact 96. This causes the capacitor 116, and any of the parallel capacitors 118 that might have been switched into the circuit, to be discharged substantially instantaneously through the electro-magnet coil 74. This causes the pole piece of the core 70 to exert a sudden and powerful attractive force on the slug 34, and thereby to press the type face 42 against the ribbon 34 to form a typing impression on the paper 32. Since this magnetic force is not applied until such time as the type face is in engagement with the ribbon, or very nearly so, the type face acts to form the typing impression with a pressing force with substantially no noise.

It will be appreciated that a given charge will be applied to an adjacent slug 44 when the single capacitor 116, connected between the bus 108 and the wire 94, is discharged. The additional capacitors 118 are connectable in parallel with the capacitor 116 by the closing of switches 120. It will be appreciated that this causes a stronger impulse to be imparted to the adjacent slug, whereby a greater typing force is applied to the ribbon. As will be appreciated, this renders it possible to provide a greater number of carbon copies, or to form a more forcible impression, if such should be desired.

It will be appreciated that the resilient arms 86 of the switch having the contacts 84 are tensioned or cocked by the flexion thereof in response to engagement by the insulated tip 80 of the switch actuator or push member 76. The capacitor 116 discharges substantially instantaneously, and cannot recharge for a predetermined finite time due to the resistor 110. Accordingly, immediately upon formation of the typing impression, the switch arms 86 straighten out by virtue of their resiliency, and thereby start the type bar back past the dashed line position to the dot-dash line position of Fig. 1. Release of the key 54 allows the key lever 50 to return to its initial position under the influence of spring 58, and the jack or dog 60 thereby snaps under the shoulder 67. It will be appreciated that the size of the resistor 110 is chosen so that the capacitor 116 readily will recharge in the time between strokes of a typist's fingers, but will not recharge sufficiently rapidly to preclude return of a key bar 36 to its initial position.

It is further set forth in my aforesaid patent application that the size of the slug 44 may be varied from one type bar to another in accordance with the area of the character of the associated type face. For instance, a larger slug is used in connection with the letter "w," while a smaller slug is used in connection with the "point" type face.

Without departing from the scope or structure of the invention as set forth in my aforesaid co-pending patent application, and as summarized hereinabove, it is possible to obtain proportional letter spacing. Reference should be had to Figs. 1-3 for an explanation thereof.

Immediately beneath the position of the slug 44 when in the operative position shown in solid lines in Fig. 1, there is positioned a flux conductor bar 122 having an enlarged lower portion in the form of a hollow cylinder 124. The flux conductor bar is made of soft iron or the like, and is mounted in place by a support 126. Normally, the flux conductor bar is positioned adjacent the lower left corner of the slug 44 as viewed in the drawing. However, the support 126 is linked to the carriage shift mechanism whereby to shift the flux conductor bar 122 to a position beneath the lower right corner of the slug as shown in dashed lines. The plunger 128 is reciprocably mounted within the hollow cylinder 124 of the flux conductor bar, and is urged outwardly thereof by a compression spring 130. The bottom end of the plunger is pivotally connected at 132 to the end of a link or lever 134 pivoted at 136, and resting against a stop 137 which prevents the plunger 128 from being forced completely from the cylinder by the spring 130. The pivotal connection 132 preferably comprises a pin-in-slot connection for providing a telescoping movement when the flux conductor bar 122 is shifted to the right to the dashed line position. The opposite end of the lever 134 is pivotally connected to a pawl or carriage escapement tooth 138 engaging with the rack 140 of the type generally found on substantially all conventional typewriters.

At the instant of printing, a certain amount of magnetic flux passes through the slug 44 into the flux conductor bar, and down to the plunger. The plunger accordingly is drawn up into the hollow cylinder, and in doing so pivots the lever 134 (in a clock-wise direction as viewed in Fig. 1). This pulls down the carriage escapement tooth and allows the carriage to advance under the usual spring bias. When the capacitor 116 has discharged through the electro-magnet coil 74, the magnetic pulse ends, and the spring 130 forces the plunger 128 back to its normal lowered position, the tooth or pawl 138 thereby engaging the rack 140, after the rack has advanced one or more tooth spaces.

It will be apparent that the amount of magnetic force determines the distance the plunger 128 is drawn into the cylinder 124. Obviously, the greater this distance, the longer the escapement tooth or pawl will be out of engagement with the carriage rack, and the further the carriage will move along under the influence of its biasing spring.

Each slug 44 is formed individually so as to control the amount of magnetic flux that will be picked up by the conductor bar. Specifically, the amount of iron in the lower part of each type slug, and the width of the bottom edge of the slug, immediately adjacent to the upper end of the flux conductor bar, will be the main controlling factor. For example, in the case of the letter "m," which is four units wide, there will be four times the amount of iron in the lower part of the slug that there will be for the letter "i," which is only one unit wide. Accordingly, the "m" type head will cause the plunger to be pulled four times deeper into the hollow cylinder of the conductor bar than for the letter "i." Accordingly, the carriage escapement tooth or pawl will be held out of engagement with the rack for four times as long, thus allowing the carriage to move along four units of space, as compared with one unit in the case of the letter "i." It will be apparent that the specific figures given are by way of illustration, since the non-linear characteristics of magnetic materials, and other factors, will require some variations from these figures.

The amount of iron in the lower portion of each slug substantially determines the amount of carriage escapement. On the other hand, the total amount of iron in each slug determines the force of the corresponding typing impression. Therefore, as will be seen in Figs. 3, 4 and 7 it may reasonably be expected that the upper portion of a slug 44, as is indicated at 44a, will be relatively wide, while the lower portion 44b may be somewhat more

narrow. The exact shape and proportions of the upper and lower parts 44a and 44b may be expected to vary from one slug to another. For example, the number "8" and the letter "n" are both two units wide for spacing purposes. However, the numeral "8" covers a considerably larger area, and necessarily will be printed more forcibly than the "n." Accordingly, there will be more iron in the upper part of the type slug for the number "8" than there will be for the letter "n," although the amount of iron in the lower part 44b of the slug necessarily will be about the same for the "8" as for the "n" since each is two units wide, and the carriage must be allowed to escape the same distance for each.

In addition, the lower part of each slug is not necessarily uniform. It is the universal practice in typewriters to place the upper and lower case characters on the same type head, and to shift from one to the other by vertical movement of the carriage on the type basket. For proper proportional spacing, compensation must be made for the frequently larger size of the upper case or capital letters as compared with the lower case letters. For example, the lower case "s" may be two units wide while the capital "S" is three units wide. A more extreme example is found wherein the lower case "f" is only one unit wide, while the capital "F" is three units wide. On the other hand, both cases of the letter "M" are four units wide.

Accordingly, there is provided a "shift" in the flux conductor bar as well as in the carriage or type basket. As has been indicated, the sliding support 126 is connected to the carriage shift, so that in the event the platen 30 is raised for the printing of a capital letter, the flux conductor bar 122 will be shifted to the right to the dashed line position of Figs. 1 and 2. The amount of iron along the bottom edge of the slug is determined from front to back (or left to right as viewed in the figures of the drawing) in accordance with the requirements of the corresponding type face. Thus, in Figs. 3 and 4, it will be observed that the left end c of the lower part 44b of the type slug is of a given width, while the right end d is of twice the width of the end c. Accordingly, when the flux conductor bar is positioned in the dashed line position for typing capital letters, twice as much flux will be picked up by the conductor bar, as when the conductor bar is in the lower case or left hand position. Accordingly, the carriage will be allowed to escape twice as far when the flux conductor bar is positioned adjacent the end d, as when it is positioned adjacent the end c.

It will be appreciated that when the flux conductor bar is nearer the main magnet, the flux will be stronger, and accordingly the end d may not necessarily be quite twice as wide as the end c. The important feature with regard both to the necessary force for printing the characters, and for the character escapement, is that the slugs have variable width and mass, both in the top portion, and in the lower portion.

In Fig. 5 there is illustrated a slug 44' wherein the ends c and d are of the same width in order to allow the carriage to escape the same distance for the upper case as for the lower case characters.

As will be appreciated, the carriage escapement pawl or dog 138 may be retracted mechanically upon depression of the spacer bar, as in the usual typewriter, or an auxiliary electro-magnetic device may be provided for this purpose.

When additional capacitors 118 are connected in the circuit for making additional copies, it is apparent that a greater magnetic force will be applied to the flux conductor bar. However, the plunger cannot be allowed to enter this bar a greater than usual distance, or the carriage would escape too far. Accordingly, a retarding spring 142 (Fig. 1) is stretched between the link or lever 134 and an anchor lever 144 which is variable in position in accordance with the number of capacitors connected in the circuit. The anchor lever may be connected to the switches 120, or independently operated. Other ex-

pedients could be used to achieve the desired carriage movement as will be appreciated.

It is to be understood that the specific example of my invention as herein shown and described is set forth for purposes of illustration. Various changes in structure will no doubt occur to those skilled in the art, and are to be understood as forming a part of my invention insofar as they fall within the spirit and scope of the appended claims.

10 The invention is claimed as follows:

1. A typewriter having a platen, a pivotally mounted type bar having a type face thereon, a key for pivoting said type bar towards the platen, and a carriage escapement, the combination comprising a magnetic slug carried by said type bar, an electro-magnet acting on said slug upon energization of said electro-magnet to urge the type face toward the platen to form a typing impression, electrical circuit means for energizing said electro-magnet, a magnetic operator positioned adjacent said slug when said electro-magnet acts thereon for activating said operator by magnetic flux passing through said slug from said electro-magnet, and means operatively connecting said operator to said carriage escapement for operation thereof upon activation of said operator.

2. In a typewriter having a platen, a plurality of pivotally mounted type bars each having a type face thereon, a plurality of keys for respectively pivoting said type bar towards said platen, and a carriage escapement, the combination for proportional letter spacing comprising a plurality of magnetic slugs, each carried by one of said type bars, an electro-magnet acting on any of said slugs upon energization of said electro-magnet to urge the corresponding type face toward the platen to form a typing impression, electrical circuit means for energizing said

35 electro-magnet, a magnet operator positioned adjacent a slug being acted upon by said electro-magnet for activating said operator by magnetic flux passing through said slug from said electro-magnet, and means operatively connecting said operator to said carriage escapement for operation thereof upon activation of said operator, the size of each slug being individually determined to control the amount of flux passing therethrough.

3. The combination set forth in claim 2 wherein the magnet operator is positioned adjacent a portion of each slug which is not facing the electro-magnet, and wherein the operator is shiftable along said adjacent portion in accordance with whether an upper case or lower case typing impression is to be made, and wherein the area of said adjacent portion varies along the direction of movement of the operator therealong, said area variation being in accordance with the variation in width of the lower case and upper case characters whereby to direct greater or lesser amounts of flux to said magnetic operator for controlling the operation of said carriage escapement in accordance with the width of the character to be typed.

4. The combination as set forth in claim 2 wherein one face of the slug confronts the electro-magnet and another face confronts the magnetic operator, the area of the electro-magnet confronting face being determined in accordance with the area of the character being printed, and the area and configuration of the operator confronting face being determined in accordance with the width of the character being typed.

5. The combination as set forth in claim 4 wherein the magnetic operator is reciprocably shifted along the confronting face of the slug in accordance with the typing of a lower case or an upper case character, and wherein the area of the operator confronting face is determined along the path of movement of the operator in accordance with the width of the upper case or lower case character being typed.

6. In a typewriter having a platen, a plurality of pivotally mounted type bars having type faces thereon, a plurality of keys for respectively pivoting said type bars towards said platen, and a carriage escapement, the com-

bination comprising a plurality of magnetic slugs each carried by one of said type bars, an electro-magnet individually acting on any of said slugs upon energization of said electro-magnet to urge the type face toward the platen to form a typing impression, electrical circuit means for energizing said electro-magnet, a magnetic flux conductor positioned adjacent the slug being acted on by the electro-magnet for conducting flux from said slug, the area of the part of each slug adjacent said flux conductor being determined in accordance with the width of the character on the corresponding type face whereby to direct an amount of flux into said conductor proportional to the width of said character, a magnetic member movable relative to said flux conductor a distance proportional to the amount of flux in said conductor, and means operatively connecting said member to said carriage escapement for effecting escapement of said carriage a distance proportional to the distance which said member is moved.

7. In a typewriter having a platen, a movably mounted type bar having a type face thereon, a key for moving

5 said type bar to bring said type face into printing proximity to the platen, and a carriage escapement, the combination comprising a magnetic portion on said type bar, an electro-magnet acting on said magnetic portion upon energization of said electro-magnet with said type face in printing proximity to said platen, electric circuit means for so energizing said electro-magnet, a magnetic operator positioned adjacent said magnetic portion when said electro-magnet acts thereon for activating said operator by magnetic flux passing through said type bar magnetic portion from said electro-magnet, and means operatively connecting said operator to said carriage escapement for operation thereof upon activation of said operator.
